UNITED STATES PATENT OFFICE.

GEORGE H. ROBERTS, OF INDIANAPOLIS, INDIANA, ASSIGNOR TO PITMAN-MOORE COMPANY, OF INDIANAPOLIS, INDIANA, A CORPORATION OF INDIANA.

DEFIBRINATER.

1,224,096.

Specification of Letters Patent. Patented Apr. 24, 1917.

Application filed July 29, 1916. Serial No. 112,149.

To all whom it may concern:

Be it known that I, GEORGE H. ROBERTS, a citizen of the United States, residing at Indianapolis, in the county of Marion and State of Indiana, have invented a new and useful Defibrinater, of which the following is a specification.

In the manufacture of certain serums, viruses, and vaccines, the desired substance is developed from the blood of the living animal, and the blood is then drawn from the animal and suitably treated to obtain such substance. In order to obtain this substance from the blood, it is necessary that such blood be freed from the fibrin which forms in it when it is drawn from the animal's body, as otherwise such fibrin causes a clotting of the blood and partial or complete loss of the desired substance. If the blood be maintained in continuous agitation from the time it is drawn from the animal's body until the formation of the fibrin is complete, the fibrin is segregated from the other part of the blood and floats thereon, and may be removed by filtration so as to leave the other part of the blood unclotted.

Heretofore this segregation of the fibrin as it forms has been almost wholly obtained by hand whipping of the blood or by hand shaking thereof. This has required a great deal of tedious labor.

It is the object of my present invention to provide a mechanical defibrinater for maintaining the blood in continuous agitation until the fibrin-forming process is complete.

The accompanying drawings illustrate my invention. Figure 1 is a vertical section through a defibrinater embodying my invention, being taken substantially on the line 1—1 of Fig. 2; Fig. 2 is a vertical section on the line 2—2 of Fig. 1; Fig. 3 is an enlarged sectional detail, showing the construction and mounting of one of the rotatable jar-supporting elements; and Fig. 4 is a section on the line 4—4 of Fig. 3.

On the top 10 of a suitable frame or table are a number of trunnion supports 11, in which are mounted trunnions 12 of a series of rotatable jar-supporting elements. These jar-supporting elements are all separate, so that they can be rotated selectively as required.

Each jar-supporting element comprises the main body 15, having a pair of curved side arms 16 which carry the trunnions 12,

which trunnions are in a line offset from the main body 15 and in the plane of an overhanging cupped finger 17 at one end of such main body and a cup 18 spring-mounted on a lever 19 pivoted on a pin 20 at the other end of such main body. The cup 18 is spring-pressed toward the finger 17 by springs 21 surrounding pins 22 which interconnect such cup and the lever 19, but is yieldable away from such finger 17 by the compression of the springs 21 to receive and resiliently hold a suitable jar 23 in which the blood to be defibrinated is placed. The bottom of the jar fits in the cup 18, and the mouth of the jar is closed by a cork 24 which is pressed into such mouth by the finger 17. The axis of the trunnions 12 passes through the jar 23 sufficiently near the center of the latter so as to prevent during the rotation of the jar-supporting member the development of sufficient centrifugal force to displace the jar; though it is not necessary that such axis should pass through the exact center of the jar. The lever 19 is provided at its opposite end from that which carries the cup 18 with a roller 26, which co-operates with a cam finger 27 on a clamping lever 28 mounted on a pivot pin 29 on the main body 15. By moving the clamping lever 28 in a counterclockwise direction (Figs. 2 and 3) to the position shown, the cam 27 forces outward the roller 26, thereby forcing the cup 18 toward the finger 17 to clamp a jar 23 in place; and the lever 28 moves sufficiently far in this counterclockwise direction so that the point which forms its nose passes beyond the line joining the centers of the roller 26 and the pivot pin 29 so as to lock the lever in this position by the expanding action of the springs 21. Turning the clamping lever 28 in the opposite direction permits the cup 18 to be moved away from the finger 17 so as to permit the insertion or removal of a jar 23.

Each jar-supporting element has at one side a driving pulley 30, which is connected by a loose belt 31 to a pulley 32 on the drive shaft 33 common to all the jar-supporting elements. This drive shaft is suitably driven in any convenient way, as by an electric motor 34 suitably connected thereto, as by a silent chain 35 and suitable sprockets. The belts 31 for the different jar-supporting elements are sufficiently loose so that unless such belts are tightened they will not drive such elements on the rotation of the shaft 110

33. In order to tighten any of the belts 31, to throw their jar-supporting elements into operation, an idler pulley 36 is mounted on an arm 37 carried by a fixed rod 38, the pivotal end of such arm 37 being bifurcated so as to fit astride a collar 39 fastened on such rod 38 by a set screw 40, so that the collar 39 prevents movement of the arm 37 axially of the rod 38, and the set screw 40 limits the movement of the idler pulley 36 away from its associated belt 31. The arm 37 has an upwardly extending finger 41 to which is pivoted a socket 42 which receives the threaded end of a rod 43 provided with a handle 44 projecting through the apron 45 of the table 10, the opening for the rod 43 being provided by a metal plate 46 which has a central hole for such rod and a lateral slot 47 for permitting the passage of a radial pin 48 carried by the rod 43 in the plane of the handle 44, which is weighted to hang in the position shown. Thus the handle 44 must be turned to bring the pin 48 into registry with the slot 47 before the rod 43 may be pushed in or drawn out to tighten or loosen the associated belt 31. By screwing the rod 43 into or out of the socket 42 the tightness which the idler pulley 36 produces in the belt 31 may be adjusted.

30 In operation, the blood from the bodies of the animals is drawn into any desired number of jars 23, the blood being whipped in the jars while it is being drawn to segregate any immediately forming fibrin, and 35 then the jars with the blood in them are placed in the several rotatable jar-supporting elements, of which there may be any desired number. The motor 34 and shaft 33 being in operation, the blood-containing 40 jar is started into rotation, as soon as it is placed in its jar-supporting element, by pushing in the corresponding handle 44 to tighten the corresponding belt 31. The rotation of the jar and the resultant agitation 45 of the blood therein segregates the fibrin as it is formed; and when the formation of the fibrin is complete the rotation of the jar may be stopped, the jar removed, and another jar of blood put in place on the 50 same jar-supporting element, without interfering with the continuous rotation of the other jar-supporting elements and the continuous agitation of the blood in the jars supported thereon.

55 I have found in practice that the agitation produced by this apparatus produces almost perfect segregation of the fibrin, and reduces the loss from blood clotting to a negligible amount.

60 I claim as my invention:

1. A defibrinator, comprising a jar-supporting element mounted for rotation, said jar-supporting element having two opposed parts for receiving and clamping a jar between them, one of such parts being spring-

mounted, a clamping member for moving said opposed parts relatively to produce a clamping and unclamping of said jar, the axis of rotation of said jar-supporting element passing through a jar when it is clamped between such opposed parts, and means for rotating said jar-supporting element. 70

2. A defibrinator, comprising a jar-supporting element mounted for rotation, said jar-supporting element having two opposed parts for receiving and clamping a jar between them, one of such parts being spring-mounted, the axis of rotation of said jar-supporting element passing through a jar when it is clamped between such opposed parts, and means for rotating said jar-supporting element. 75

3. A defibrinator, comprising a jar-supporting element mounted for rotation, said jar-supporting element having two opposed parts for receiving and clamping a jar between them, one of such parts being spring-mounted, a clamping member for moving said opposed parts relatively to produce a clamping and unclamping of said jar, and means for rotating said jar-supporting element. 80

4. A defibrinator, comprising a jar-supporting element mounted for rotation, said jar-supporting element having two opposed parts for receiving and clamping a jar between them, one of such parts being spring-mounted, and means for rotating said jar-supporting element, the axis of such rotation being transverse to the axis of the jar. 90

5. A defibrinator, comprising a jar-supporting element mounted for rotation about an axis transverse to the jar axis, said jar-supporting element having two opposed parts for receiving and clamping a jar between them, one of such parts being spring-mounted, a driving motor, and means for drivingly connecting and disconnecting said motor and said jar-supporting element. 105

6. A defibrinator, comprising a motor-driven shaft, a plurality of jar-supporting elements separately connected to said shaft by loose belts, said jar-supporting elements being mounted for independent rotation, and an idler pulley associated with each 110 loose belt for tightening it, said idler pulley being mounted on a swinging arm, and a push rod of adjustable length connected to said swinging arm for operating it and provided with a stop for holding the pulley 115 in belt-tightening position, said stop being adjustable by adjusting the length of said rod.

7. A defibrinator, comprising a motor-driven shaft, a plurality of jar-supporting elements separately connected to said shaft by loose belts, said jar-supporting elements being mounted for independent rotation, and an idler pulley associated with each 125 loose belt for tightening it. 130

8. A defibrinator, comprising a driving shaft, a plurality of jar-supporting elements mounted for independent rotation, and means for connecting each of said jar-supporting elements to said shaft or disconnecting it therefrom without affecting the other jar-supporting elements, each of said jar-supporting elements being arranged to support a jar so that the axis of rotation passes through the jar.
9. A defibrinator, comprising a driving shaft, a plurality of jar-supporting elements mounted for independent rotation, and means for connecting each of said jar-supporting elements to said shaft or disconnecting it therefrom without affecting the other jar-supporting elements, each of said jar-supporting elements being provided with opposed members which are relatively spring-pressed toward each other for clamping a jar between them with the axis of rotation of the jar-receiving element passing through the jar, and a clamping mem-
- ber for moving said opposed members relatively to produce clamping and unclamping of said jar.
10. A defibrinator, comprising a driving shaft, a plurality of jar-supporting elements mounted for independent rotation, and means for connecting each of said jar-supporting elements to said shaft or disconnecting it therefrom without affecting the other jar-supporting elements, each of said jar-supporting elements being provided with opposed members which are relatively spring-pressed toward each other for clamping a jar between them, and a clamping member for moving said opposed members relatively to produce clamping and unclamping of said jar.

In witness whereof, I have hereunto set my hand at Indianapolis, Indiana, this twenty-eighth day of June, A. D. one thousand nine hundred and sixteen.

GEORGE H. ROBERTS.
